LAMP OR SIMILAR ARTICLE

Hedwig A. Baur Leu, 225 W. Woodlawn, La Grange, Ill.

Filed Jan. 29, 1964, Ser. No. 78,405

Term of patent 3½ years

(Cl. D48—20)

FIG. 1 is a perspective view of a lamp showing my new design;

FIG. 2 is a perspective view thereof taken from the side generally opposite that shown in FIG. 1;

FIG. 3 is a perspective view thereof taken generally from the left side as seen in FIG. 1; and

FIG. 4 is a perspective view thereof taken generally from the right side as seen in FIG. 1.

The dominant features of the design are shown in full lines.

I claim:

The ornamental design for a lamp or similar article, substantially as shown and described.
